RAILWAY SIGNALING SYSTEM

Leslie R. Allison, Forest Hills, Pa., assignor to The Union Switch & Signal Company, Swissvale, Pa., a corporation of Pennsylvania

Application February 21, 1940, Serial No. 320,146

3 Claims. (Cl. 246—38)

My invention relates to a railway signaling system having track circuits employing coded or periodically interrupted current.

It has heretofore been proposed to provide means operable in the event an insulated joint separating two track sections is defective to establish a "lockout" circuit to supply steady uncoded energy to the section in the rear of the defective joint so that this energy will feed over the defective joint and maintain the track relay of the section in advance of the defective joint constantly energized to thereby cause the signal controlled by the track relay to display its most restrictive indication.

It has also been proposed heretofore to provide a system of the type referred to and to arrange the system so that after the contacts of the track relay have been released for a time interval and code following operation of the contacts is initiated, the "lockout" or steady energy supply circuit will not be established on the first movement of the track relay contacts to their picked up position. This arrangement was devised to prevent "cascading" action in the event an insulated joint separating two sections is defective and steady energy is supplied to the section in the rear, or if steady energy is supplied to a track section to discontinue operation of a highway crossing signal.

In such a system the "lockout" circuit for supplying steady energy to the adjacent section in the rear of a defective joint is established on a movement of the track relay contacts to their picked up position subsequent to their first movement to such position, while the "lockout" circuit is interrupted if the track relay continues to respond to coded energy. A system embodying these characteristics is shown in an application of Ralph R. Kemmerer, Serial No. 282,185, filed June 30, 1939, for Railway signaling system, now U. S. Patent No. 2,215,904, granted Sept. 24, 1940.

It is an object of my invention to provide a system of the type described which will be non-cascading in operation and which employs less apparatus than the system heretofore known has required.

A further object of my invention is to provide an improved railway signaling system incorporating a "lockout" circuit, the system being arranged so that it is non-cascading in operation.

Another object of my invention is to provide code detecting means adapted for use in a coded signaling system to ascertain when a code following relay is responding to coded or periodically

interrupted energy, this means being arranged so that on initiation of code following operation of the relay the means will not respond to such operation of the relay until the contacts of the relay have been moved between their picked-up and released positions a plurality of times.

A further object of my invention is to provide code detecting means of the type described and which is arranged to quickly detect when the code following relay ceases to respond to coded energy.

Another object of my invention is to provide a coded railway signaling system which is arranged so that if a train enters a section in which the track relay is energized with steady uncoded energy, the equipment will not operate to cause a flash of the yellow or caution lamp of the signal for such section.

Another object of my invention is to provide an improved coded railway signaling system.

Other objects of the invention and features of novelty will be apparent from the following description taken in connection with the accompanying drawing.

I shall describe three forms of apparatus embodying my invention, and shall then point out the novel features thereof in claims.

In the drawing:

Fig. 1 is a diagram of a railway signaling system employing the improved code detecting means provided by this invention,

Fig. 2 is a diagram of a railway signaling system incorporating the improved non-cascading lockout circuit provided by this invention, and

Fig. 3 is a fragmentary diagrammatic view showing a modification which may be employed in the system shown in Fig. 2.

Referring to Fig. 1 of the drawing, there is shown therein a stretch of railway track having track rails 1 and 2 over which traffic normally moves in the direction indicated by the arrow. The track rails of the track stretch are divided by insulated joints 3 into the customary successive track sections which are identified as 10T, 11T, and 12T.

The particular track stretch shown in Fig. 1 is intended for use in a railway system employing steam for propulsion purposes, and while alternating current is employed in the track circuits, it should be understood that coded direct current may be employed if desired.

Each of the track sections has positioned at the entrance end thereof a wayside signal S which indicates to an approaching train the nature of the traffic conditions in the sections

immediately ahead. The particular signal shown is of the well-known color light type having three lamps G, Y, and R. It should be understood, however, that my invention is not limited to the use of this type of signal, and that any other suitable type of signal may be employed if desired.

The rails of each of the track sections form a part of a track circuit to which coded alternating current signal control energy normally is continuously supplied through a track transformer TT, the secondary winding of which is connected with the rails at the exit end of the section. The connection of the transformer with the track rails includes the usual current limiting reactor 6. The energy supplied to the track circuits is derived from any suitable source and may be distributed throughout the track stretch by a transmission line, not shown. In the drawing the reference characters BX and CX designate terminals which are supplied from such source.

Each signal location has associated therewith a source of direct current, such as a primary or storage battery, not shown, the terminals of which are designated B and C in the drawing.

The signaling system shown in Fig. 1 is of the three-indication variety and makes use of track circuit energy of two different codings. These codings are produced by code transmitters CT which interrupt the supply circuits of the track transformers a definite number of times a minute according to traffic or other conditions ahead. In the form shown each code transmitter CT is provided with two circuit making and breaking contacts designated 75 and 180 which are continuously actuated by a motor or other suitable mechanism at speeds such as to produce codes consisting of 75 and 180 energy pulses per minute, respectively, the energy pulses being separated by intervals of equal duration in which no energy is supplied.

Each of the track circuits includes a code following track relay TR having its operating winding connected through a resonant unit RU to the track rails of the track section adjacent the entrance end thereof. The resonant units RU include a transformer, a capacitor, and a reactor arranged and proportioned so as to freely pass alternating current of the frequency employed in the signal control circuits, but so as not to pass current of a different frequency.

Each of the resonant units includes, in addition, a rectifier for rectifying the current supplied through the resonant unit to the winding of the track relay.

In the system shown in Fig. 1, energy of one or the other of the two previously described code frequencies, namely 75 or 180, is normally fed to the track circuits at all times. However, it may be desired at times to supply steady uncoded energy to a track circuit to discontinue operation of a highway crossing signal, as explained in the application of Ralph R. Kemmer identified above.

Similarly, where the track sections are long, it may be desired to divide a track section into two parts, and to provide means at the junction between the two parts to repeat to the rear portion the code supplied to the forward portion of the section. It may also be desired to employ "back contact coding" at the cut sections to prevent code distortion. This will result in the supply of steady uncoded energy to the rearward portion of the section when the forward portion of the section is occupied. One form of apparatus which may be employed at the cut sections to

provide this "back contact coding" is shown in an application of Charles B. Shields and Herman G. Blosser, Serial No. 275,146, filed May 23, 1939, for Railway traffic controlling apparatus, now U. S. Patent No. 2,211,174, granted Aug. 13, 1940.

Each of the track relays has associated therewith auxiliary relays FSA and H which serve to determine when the contacts of the track relay TR are responding to coded energy, and an auxiliary relay J which determines when the track relay is responding to energy of the 180 code frequency. The auxiliary relays FSA and H control the supply of energy to the track circuit of the adjacent track section in the rear, while the auxiliary relays H and J jointly control the signal for the associated track section.

The contacts 15 and 16 of the track relay 11TR are connected to terminal B of the local source of direct current. Contact 16 when picked up engages a contact which is connected to one terminal of the winding of relay 11FSA, the other terminal of which is connected to terminal C of the source of current. A snubbing resistor 20 is connected across the terminals of the winding of the relay 11FSA to render the relay contacts slow in releasing.

Contact 17 of relay 11TR is connected to one element of an electrolytic condenser 11EC, while the other element of the condenser is connected to terminal C of the source of direct current and also to one terminal of the winding of relay 11H, the other terminal of which is connected to a contact which is engaged by contact 17 when contact 17 is picked up. Contact 17 when released engages a contact which is connected to contact 22 of relay 11FSA, while contact 22 when picked up engages a contact which is connected to terminal B of the source of direct current.

A snubbing resistor 23 is connected across the terminals of the winding of relay 11H to render the relay contacts slow in releasing.

Contact 15 of track relay 11TR controls the supply of current to the primary winding 25 of the decoding transformer 11DT. Contact 15 when picked up engages a contact which is connected to one end terminal of the transformer primary winding, and when released engages a contact which is connected to the other end terminal of the transformer primary winding, while the center terminal of the winding 25 is connected to terminal C of the local source of direct current.

The secondary winding 26 of the transformer 11DT is connected to resonant unit 11RUA which is connected to the terminals of the winding of relay 11J. The resonant unit 11RUA comprises a reactor and a capacitor arranged and proportioned to freely pass energy of the frequency supplied by the secondary winding 26 when the contacts of track relay 11TR are responding to energy of the 180 code frequency, but so as not to pass a substantial amount of energy of the frequency present when the track relay contacts are responding to coded energy of a different frequency, as, for example, the 75 code frequency. The resonant unit 11RUA includes a rectifier which rectifies the current supplied to the winding of relay 11J.

The track transformer 10TT has a primary winding 28, one terminal of which is connected to terminal CX of the source of signal control current, and the other terminal of which is connected to contact 29 of relay 11FSA. Contact 29 when released engages a contact which is connected to contact 75 of the code transmitter 11CT, while contact 29 when picked up engages

a contact which is connected to contact 30 of relay 11H.

Contact 30 when released engages a contact which is connected to contact 75 of the code transmitter, while contact 30 when picked up engages a contact which is connected to contact 180 of code transmitter 11CT.

The contacts 15 and 180 of code transmitter 11CT intermittently engage front contacts which are connected by wire to terminal BX of the 10 source of signal control current.

The relay 11H has a contact 32 which is constantly connected to terminal B of the source of direct current, and which when released engages a contact which is connected to one terminal of the red or stop lamp R, the other terminal of which is connected to terminal C of the source of current.

Contact 32 when picked up engages a contact which is connected to contact 33 of relay 11J. Contact 33 when released engages a contact which is connected to a terminal of the yellow or caution lamp Y, the other terminal of which is connected to terminal C of the source of current. Contact 33 when picked up engages a contact which is connected to one terminal of the green or clear lamp G, the other terminal of which is connected to terminal C of the source of current.

The equipment shown in Fig. 1 is shown in the condition which it assumes when the track stretch is vacant for at least one section in advance of section 11T. At this time the equipment associated with section 12T operates to supply energy of the 180 code frequency to the 30 transformer 11TT so that energy of this code frequency is supplied to the rails of section 11T, and thus to the winding of track relay 11TR with the result that the contacts of the track relay 11TR are picked up and released at this 40 code frequency.

During the picked up periods of the track relay contacts, contact 16 establishes the circuit to supply energy to the winding of relay 11FSA. The supply of current to this relay winding is interrupted during the released periods of the track relay contacts, but the contacts of the relay 11FSA are slow enough in releasing to remain picked up during the intervals between the supply of impulses of energy to the relay 50 winding.

As the contacts of relay 11FSA are picked up, contact 22 establishes connection from terminal B of the source of direct current to back point of contact 17 of the track relay 11TR. Accordingly, during the released periods of the track relay contacts, a circuit is established to charge the condenser 11EC, this circuit being traced from terminal B of the source of current through contact 22 of relay 11FSA, contact 17 of relay 11TR to one element of the condenser 11EC, the other element of which is connected to terminal C of the source of current. As a result of connection of the two elements of the condenser to the terminals of the source of current, a charge is built up between the condenser elements.

When contact 17 of the track relay 11TR is picked up, the circuit for charging the condenser is interrupted and a circuit is established to supply energy from the condenser to the winding of relay 11H. This circuit is traced from one of the condenser elements through contact 17 of relay 11TR to one terminal of the winding of 70

relay 11H, the other terminal of which is connected to the other element of the condenser.

It will be seen, therefore, that when the contacts of the track relay 11TR are responding to coded energy, contact 22 of relay 11FSA is picked up so that during the released periods of the track relay contacts, a circuit is established to charge the condenser 11EC, while during the picked up periods of the track relay contacts, a circuit is established to supply energy from the condenser to the winding of relay 11H. The condenser 11EC and the relay 11H are proportioned so that the impulses of energy supplied from the condenser to the relay winding are of such magnitude that the contacts of the relay will be picked up, and will remain picked up during the intervals between the supply of impulses of current to the relay winding, when the track relay 11TR is responding to coded energy of either of the frequencies employed in the control of the signals. Accordingly, since the track relay 11TR is responding to coded signal control energy, the contacts of relays 11FSA and 11H are picked up.

As it is assumed that section 12T is not occupied at this time, energy of the 180 code frequency is supplied to the rails of section 11T. During the released periods of the track relay contact 15, energy is supplied to the lower portion of the primary winding 25 of the decoding transformer 11DT, while during the picked up periods of the contact 15 energy is supplied to the upper portion of the primary winding 25. As a result of the alternate energization of the two portions of the winding, energy is induced in the secondary winding 26, and since the track relay is responding to energy of 180 code frequency, the frequency of the current induced in the transformer secondary winding 26 is such that it is freely passed by the resonant unit 11RUA, and sufficient energy is supplied to the winding of relay 11J to maintain the contact of the relay picked up.

As the contacts of relays 11J and 11H are picked up, the circuit for supplying energy to the green lamp G of signal 11S is complete, and this lamp is lighted to indicate that there are at least two clear sections in advance of the signal 11S.

As the contacts of the relays 11FSA and 11H are picked up, the circuit for supplying energy of the 180 code frequency to the transformer 11TT is established. This circuit is traced from terminal BX of the source of signal control current through contact 180 of code transmitter 11CT, front contact 30 of relay 11H, front contact 29 of relay 11FSA, and primary winding 50 to terminal CX of the source of signal control current.

Operation of equipment on passage of a train in normal direction of traffic

When a train moving from left to right enters section 11T, the wheels and axles of the leading vehicle shunt the track relay 11TR and the contacts of this relay thereafter remain in their released position. As contact 16 does not engage its front contact, no energy is supplied to the winding of relay 11FSA and the contacts of this relay thereupon become released. Likewise, as contact 17 does not engage its front contact, impulses of energy are no longer supplied from the condenser 11EC to the relay 11H and the contacts of relay 11H become released, while as contact 22 of relay 11FSA is released, the circuit for supplying energy to the condenser 11EC is interrupted.

On entrance of the train into the track stretch

with resultant shunting of the track relay $11TR$, the relay contacts become released and contact 17 engages its back contact to establish the circuit for supplying energy to the condenser $11EC$. This circuit is complete as long as the contact 22 of relay $11FSA$ remains picked up, while because of the slow releasing characteristics of relay $11FSA$ the contact 22 of the relay remains picked up for an appreciable time interval subsequent to movement of the track relay contacts to their released position. Accordingly energy is supplied to the condenser $11EC$ for a period of time long enough to build up a charge of substantial value between the elements of the condenser $11EC$.

The characteristics of the condenser $11EC$ are such, however, that any charge built up between the condenser elements at the time the contacts of the track relay and of the relay $11FSA$ become released will be quickly dissipated by leakage between the condenser elements so that on subsequent picking up of the track relay contacts little or no energy is supplied from the condenser to the winding of relay $11H$. The characteristics of the condenser $11EC$ are such that the charge between the condenser elements is reduced to a low ineffective value in a shorter time than is required for a train to traverse a track section.

As the contacts of the track relay remain in their released positions, no energy is induced in the secondary winding 26 of transformer $11DT$, and hence no energy is supplied to the relay $11J$ and the contact of that relay becomes released.

As a result of the release of the contact 32 of relay $11H$, the circuit for illuminating the green lamp G is interrupted and the circuit for lighting the red lamp R is established.

On release of contact 29 of relay $11FSA$, or on release of contact 30 of relay $11H$, the circuit traced above for supplying energy of the 180 code frequency to the transformer $10TT$ is interrupted, and a circuit is established to supply energy of the 75 code frequency to the transformer $10TT$. This circuit includes contact 15 of code transmitter $11CT$, back contact 29 of relay $11FSA$, and winding 28 .

When the rear of the train vacates section $10T$, the energy of 75 code frequency supplied to the rails of that section feeds to the track relay of the section, and the equipment associated therewith operates as hereinafter explained in detail to light the yellow or caution lamp Y of the associated signal, and to supply energy of the 180 code frequency to the section in the rear.

When the train enters section $12T$, the track relay for that section is shunted, and the equipment associated therewith operates as described in detail in connection with section $11T$ to condition the signal to display its red or stop indication, and to supply energy of the 75 code frequency to the rails of section $11T$.

As long as any portion of the train remains in section $11T$, the track relay $11TR$ is shunted, but when the rear of the train vacates the section $11T$, the energy of 75 code frequency will feed to the track relay $11TR$ and effect code following operation of the contacts thereof. On the first picked up period of the track relay contacts contact 16 engages its front point of contact and energy is supplied to the winding of relay $11FSA$ so that the contacts of this relay become picked up.

On the first movement of the track relay contacts to their picked up positions a circuit is established by contact 17 to supply current from the condenser $11EC$ to the winding of relay $11H$,

but at this time little or no charge is present between the condenser elements, and no energy, or too little energy, is supplied to the winding of relay $11H$ to effect picking up of the relay contacts.

On the first released period of the track relay contacts following their first picked up period energy is supplied over back contact 17 of the track relay to condenser $11EC$ since contact 22 of relay $11FSA$ is picked up at this time.

Accordingly a charge is established between the elements of the condenser $11EC$ so that on the next or second picked up period of the track relay contacts energy is supplied from the condenser to the winding of relay $11H$ and the contacts of relay $11H$ are picked up. As explained above, on subsequent picked up periods of the track relay contacts impulses of current are supplied from the condenser to the winding of relay $11H$ to maintain the contacts of relay $11H$ picked up.

On picking up of contact 29 of relay $11FSA$ the previously traced circuit for supplying energy of the 75 code frequency to the transformer $10TT$ is interrupted, but the supply of energy of this frequency is continued over the circuit which includes back contact 30 of relay $11H$, and front contact 29 of relay $11FSA$ until contact 30 of relay $11H$ becomes picked up.

When the contacts of relays $11FSA$ and $11H$ are both picked up, the supply of energy of 75 code frequency to the transformer $10TT$ is interrupted, and the previously traced circuit for supplying energy of the 180 code frequency to the transformer $10TT$ is established.

At this time as the track relay $11TR$ is responding to energy of the 75 code frequency, the frequency of the current induced in the secondary winding 26 of the transformer $11DT$ is such that too little current is passed by the resonant unit $11RUA$ to effectively energize the winding of relay $11J$, and hence the contact of relay $11J$ remains released. As contact 32 of relay $11H$ is picked up and contact 33 of relay $11J$ is released, the circuit for illuminating the red lamp R is interrupted, and the circuit for lighting the yellow or caution lamp Y is established.

When the train has advanced far enough in the track stretch to vacate section $12T$, the track relay for that section responds to energy of the 75 code frequency supplied thereto, while the equipment associated with that track relay operates as described in detail above to supply energy of the 180 code frequency to the rails of section $11T$.

On this change in the frequency of the code supplied to the rails of section $11T$, the contacts of the relay $11TR$ operate at a correspondingly more rapid rate, and the resonant unit $11RUA$ passes sufficient energy to effect picking up of the contact of relay $11J$. As a result of picking up of the contact of relay $11J$, the yellow or caution lamp Y is extinguished, while the green or proceed lamp G is lighted, and the supply of energy of 180 code frequency to the section $10T$ is continued.

Operation of equipment when a train enters a section to which steady energy is supplied

For purposes of illustration it will be assumed that the section in advance of section $11T$ is occupied and that as a result of such occupancy, steady uncoded energy is supplied to the relay $11TR$. As pointed out above, this supply of steady energy might be for the purpose of dis-

continuing operation of a highway crossing signal, not shown, or it may be incidental to the use of "back contact coding" apparatus at a cut section.

When steady energy is supplied to the track relay 11TR, the contacts of relay 11TR are held picked up and contact 16 establishes the circuit to supply energy to the winding of relay 11FSA so that the contacts of relay 11FSA are maintained picked up.

As the track relay contacts are held in their picked up positions, contact 17 engages its front contact to establish the circuit from the condenser 11EC to the winding of relay 11T, but since the condenser is not periodically charged, no energy is available to energize the winding of relay 11H and the contacts of this relay are released.

As the contacts of relay 11H are released, contact 29 maintains the circuit for supplying energy of the 75 code frequency to the transformer 10TT, while contact 32 maintains the circuit for illuminating the red or stop lamp R of signal 11S.

If under these conditions a train enters section 11T, the track relay 11TR will be shunted and its contacts will be released. On release of contact 16 the circuit for supplying energy to the winding of relay 11FSA is interrupted, while on release of contact 17 the circuit for charging the condenser 11EC is established, and is complete until contact 22 of relay 11FSA becomes released which occurs shortly after release of the track relay contacts.

However, as a result of release of contact 17 of the track relay 11TR, the circuit for supplying energy to the winding of relay 11H is interrupted, and continues to be interrupted until the track relay contacts are picked up, which does not occur until the track section is vacated. Accordingly, on release of the track relay contacts the relay 11H remains deenergized, and contact 32 maintains the circuit for illuminating the red or stop lamp R, while there is no possibility that the contact 32 of relay 11H will be momentarily picked up to cause a flash of the yellow or caution lamp Y.

As the train proceeds through the track stretch and the rear of the train vacates section 11T, steady uncoded energy will again be supplied to the rails of section 11T and the contacts of the track relay 11TR will again become picked up. On picking up of the track relay contact 16 energy is supplied to the winding of relay 11FSA. At this time the charge built up in the condenser 11EC will have been dissipated, and on picking up of contact 17 of the track relay no energy, or insufficient energy, will be supplied from the condenser to the winding of relay 11H to effect picking up of the relay contacts. Accordingly the contacts of relay 11H will remain released and no flash of the yellow or caution lamp Y occurs at this time.

From the foregoing it will be seen that the system shown in Fig. 1 is arranged so that the H relay is energized when and only when the code following track relay is responding to coded energy, and, furthermore, that when code following operation of the track relay is initiated, energy is not supplied to the winding of relay H until the track relay contacts have moved between their picked up and released positions a plurality of times. This prevents momentary energization of the H relay on release of the track relay contacts at a time when the track

relay is steadily energized. This prevents a flash of the caution or yellow lamp Y at such times which would occur if the H relay were to be momentarily energized.

5 *Construction of the system shown in Fig. 2 of the drawing*

In Fig. 2 of the drawing there is shown a diagram of a portion of a railway signaling system incorporating the improved code detecting means provided by this invention.

The system shown in Fig. 2 of the drawing is particularly intended for use on a railroad employing electric current for propulsion purposes, and operates to provide a non-cascading "lock-out" circuit, the system being arranged so that it requires less apparatus than the systems heretofore proposed have required.

As the railroad shown in Fig. 2 of the drawing employs electric current for propulsion purposes, impedance bonds 4 are provided to conduct propulsion current around the insulated joints 3 which divide the rails 1 and 2 into the track sections 15T, 16T, 17T, etc. In addition, as the railroad employs electric current for propulsion purposes, alternating current is employed in the track circuits for signal control purposes. This current is of any suitable frequency, such as 100 cycles per second, and is distributed throughout the track stretch in any suitable manner, such as by a transmission line not shown.

Each of the track sections has a code following relay TR which is connected through a suitable resonant unit RU of the type employed in the system shown in Fig. 1 to the track rails of the track section adjacent the entrance end thereof.

The track relays each have associated therewith auxiliary relays A, F, G, H and J which cooperate to control the supply of coded energy to the track circuit of the adjacent track section in the rear, and to also control the signal for the track section with which the relays are associated.

The signal system shown in Fig. 2 of the drawing is the same as that shown in Fig. 1 with respect to features not specifically mentioned and the description thereof will not be repeated.

The equipment of this system is shown in the condition which it assumes when the track stretch is vacant for at least one block in advance of section 16T. At this time the equipment associated with section 17T is conditioned to supply energy of the 180 code frequency to the rails of section 16T, while the contacts of all of the auxiliary relays associated with the track relay 16TR are picked up.

The winding of relay 16A is energized by current supplied over a holding circuit which is traced from terminal B of a local source of direct current through contact 40 of relay 16G and winding of relay 16A to terminal C of the local source of direct current. A snubbing resistor 41 is connected across the terminals of the winding 16A to render the relay contacts slow in releasing.

As the winding of relay 16A is energized, its contact 42 is picked up to establish connection from terminal B of the source of direct current to back point of the track relay contact 44. The track relay contact 44 is connected to one element of an electrolytic condenser 16EC, the other element of which is connected to one terminal of the winding of relay 16F and also to terminal C of the source of direct current.

Accordingly during the released periods of the

track relay contact 44 energy is supplied to the condenser 16EC to build up a charge between the elements thereof, while during the picked up periods of the contact 44 it engages a contact which is connected to the other terminal of the winding of relay 16F so that at these times impulses of energy are supplied from the condenser 16EC to the winding of relay 16F. These impulses of energy are of sufficient value to maintain the contacts of the relay 16F picked up. The relay 16F is of a type which is slow releasing so that its contacts remain picked up during the intervals between the supply of impulses of current thereto.

The winding of relay 16G is energized by current supplied over a circuit which is traced from terminal B of the source of current through front contact of relay 16G, front contact 47 of relay 16F, and winding of relay 16G to terminal C of the source of current. As long as the contact 47 is picked up a snubbing resistor 48 is connected across the terminals of the winding of relay 16G and renders the relay contacts slow in releasing.

Relay 16H is energized by current supplied over the circuit which is traced from terminal B of the source of current through front contact 50 of relay 16H, front contact 51 of relay 16G, and winding of relay 16H to terminal C of the source of current. A snubbing resistor 52 is connected across the winding of relay 16H to render the relay contacts slow in releasing.

During the picked up periods of track relay contact 53 it engages a contact which is connected to one end terminal of the primary winding 54 of the decoding transformer 16DT. During the released periods of contact 53 it engages a contact which is connected to the other end terminal of the primary winding 54, while the center terminal of the primary winding is connected to contact 56 of relay 16H. As contact 56 is picked up at this time it engages a contact which is connected to terminal C of the source of direct current. Accordingly as a result of movement of contact 53 of relay 16TR between its two positions, the end portions of the primary winding 142 are alternately energized, and current is induced in the secondary winding 57, while this current is supplied through the resonant unit 16RUA to the winding of relay 16J. The resonant unit 16RUA includes a rectifier which rectifies the current supplied to relay 16J, and the current supplied thereto is sufficient to maintain the contacts of the relay picked up.

As the contacts of relays 16F, 16G, and 16H are picked up, the circuit for supplying energy of the 180 code frequency to the transformer 15TT is established, and is traced from terminal BX of the source of signal control current through contact 189 of code transmitter 16CT, front contact 60 of relay 16H, front contact 51 of relay 16G, and front contact 62 of relay 16F to one terminal of the primary winding 64 of transformer 15TT, the other terminal of which is connected to terminal CX of the source of signal control current. Accordingly energy of the 180 code frequency is supplied to section 15T, and the equipment associated at that section will respond to this coded energy.

As the contacts of relays 16H and 16J are picked up, the circuit for illuminating the green lamp G of signal 16S is established and is traced from terminal B of the source of current through front contact 65 of relay 16H, and front contact 67 of relay 16J to one terminal of green lamp G,

the other terminal of which is connected to terminal C of the source of current.

Normal operation of the equipment on passage of a train

When a train moving in the normal direction of traffic, that is from left to right, enters the section 16T, it shunts the track relay 16TR and the contacts of that relay thereafter remain in their released position. As contact 44 does not periodically engage its front contact, energy is not supplied from the condenser 16EC to the winding of relay 16F and the contacts of relay 16F thereupon become released.

On release of the contacts of relay 16F, contact 47 interrupts the previously traced circuit for energizing the winding of relay 16G. In addition, the circuit for connecting the snubbing resistor 48 in parallel with the relay winding is interrupted, and, therefore, the contacts of relay 16G quickly become released.

On release of the contact 51 of relay 16G, the circuit for energizing the winding of relay 16H is interrupted, and the contacts of that relay thereupon become released so that contact 56 of relay 16H interrupts the circuit of the primary winding 54 of transformer 16DT.

In addition, on release of contact 49 of relay 16G the circuit for energizing the winding of relay 16A is interrupted and the contacts of that relay become released.

As the contacts of the track relay 16TR no longer continue to respond to coded energy and as the circuit of the transformer primary winding 54 is interrupted by contact 56 of relay H, no current is induced in secondary winding 57 of transformer 16DT, and hence current is not supplied through the resonant unit 16RUA to energize the winding of relay 16J and the contact of that relay becomes released.

As a result of the release of contact 65 of relay 16H, the circuit for illuminating the green lamp G of signal 16S is interrupted, while the circuit for illuminating the red lamp R is established and includes back contact 65 of relay 16H.

On release of contact 62 of relay 16F the previously traced circuit for supplying energy of the 180 code frequency to transformer 15TT is interrupted, while on release of contact 61 of relay 16G the circuit for supplying energy of the 75 code frequency to the transformer 15TT is established.

The circuit for supplying energy of 75 code frequency to the transformer 15TT is traced from terminal BX of the source of signal control energy through back contact 61 of relay 16G, back contact 62 of relay 16F, and contact 75 of code transmitter 16CT to a terminal of the winding 64 of transformer 15TT, the other terminal of which is connected to terminal CX of the source of signal control energy.

As the train continues through the track stretch and enters section 17T, the track relay of that section is shunted, and the equipment associated therewith operates in the manner described in detail in connection with section 16T so that the supply of energy to transformer 15TT is changed from the 180 code frequency to the 75 code frequency.

As long as any portion of the train remains in section 16T, the track relay 16TR continues to be shunted, but when the rear of the train vacates section 16T, the energy of 75 code frequency supplied through the transformer 15TT will feed

to the track relay and effect code following operation of the relay contacts. On the first movement of the track relay contacts to their picked up position, contact 53 completes the pick-up circuit for energizing the winding of relay 16A. The circuit for energizing this relay winding includes front contact 53 of track relay 16TR, back contact 69 of relay 16F, and back contact 40 of relay 16G to one terminal of the winding of relay 16A, the other terminal of which is connected to terminal C of the source of current. As a result of energization of the winding of relay 16A, the contact 42 of this relay becomes picked up so that on the next or first released period of the track relay, contact 44 completes the circuit for supplying energy to the condenser 16EC. Accordingly a charge is established on the condenser 16EC at this time.

On the next or second picked up period of the track relay contacts, contact 44 engages its front point of contact with the result that an impulse of energy is supplied from the condenser 16EC to the winding of relay 16F to effect picking up of the contacts of this relay.

On picking up of the contacts of relay 16F contact 69 is picked up and interrupts the previously traced circuit for supplying energy to the winding of relay 16A, while contact 47 of relay 16F establishes a circuit to supply energy to the winding of relay 16G on the next or second released period of the track relay contacts.

On picking up of contact 69 of relay 16F the circuit for supplying energy to the winding of relay 16A is interrupted, but a stick circuit is established to supply energy to the winding of relay 16F as long as the contacts of relay 16G remain released. This stick circuit is traced from terminal B of the source of current through front contact 53 of the track relay 16TR, front contact 69 of relay 16F, and back contact 70 of relay 16G to one terminal of the winding of relay 16F, the other terminal of which is connected to terminal C of the source of current.

The energy supplied over the above traced stick circuit to the winding of relay 16F insures that the contacts of relay 16F will be held picked up even if the contacts of relay 16A should become released so that energy is not supplied to the condenser 16EC to charge it during the released period of the track relay contacts.

On the next or second released period of the track relay contacts energy is supplied to the winding of relay 16G over the pick-up circuit which is traced from terminal B of the source of current through back contact 53 of relay 16TR, back contact 45 of relay 16G, front contact 47 of relay 16F, and winding of relay 16G to terminal C of the source of current. As soon as the winding of relay 16G is energized, the relay contacts become picked up and contact 45 interrupts the just traced pick-up circuit for supplying pick-up energy to the winding of relay 16G, while the stick circuit traced in detail above is established to maintain the winding of relay 16G energized as long as contact 47 of relay 16F remains picked up.

On picking up of the contacts of relay 16G contact 40 establishes the previously traced holding circuit for supplying energy to the winding of relay 16A. The circuit for supplying pick-up energy to the winding of relay 16A was interrupted when the contact 69 of relay 16F became picked up, which occurred on the second picked

up period of the track relay contacts, while the holding circuit for supplying energy to the winding of relay 16A is established on picking up of contact 40 of relay 16G which occurs on the second released period of the track relay contacts. The contacts of the relay 16A are rendered slow in releasing by the snubbing resistor 41, and the relay and its resistor are arranged and proportioned so that the contact 42 of this relay will remain picked up throughout the interval between the time at which contact 69 of relay 16F becomes picked up and the time at which contact 40 of relay 16G becomes picked up. Accordingly the contacts of relay 16A will be maintained picked up continuously.

On the next or third picked up period of the track relay contacts, energy is supplied to the winding of relay 16H over the circuit which is traced from terminal B of the source of current through front contact 53 of relay 16TR, back contact 50 of relay 16H, front contact 51 of relay 16G, and winding of relay 16H to terminal C of the source of current. On picking up of the contacts of relay 16H, contact 50 interrupts the above traced circuit, while this contact establishes the stick circuit to maintain the relay winding energized as long as contact 51 of relay 16G is maintained picked up.

It will be seen, therefore, that on the third picked up period of the track relay contacts the relays 16A, 16F, 16G, and 16H are all energized. It will be seen also that the relays 16A, 16G, and 16H are thereafter maintained energized by current supplied over stick circuits, and not by current supplied over circuits including contacts of the track relay 16TR. The relay 16F, however, continues to be supplied with current impulses from the condenser 16EC, while the condenser is recharged by current supplied over the back contact of track relay contact 44.

It will be seen also that when code following operation of the contacts of the track relay 16TR has continued long enough to effect picking up of the contacts of the relay 16H, contact 56 of relay 16H establishes connection from the center terminal of the primary winding of transformer 16DT to terminal C of the local source of direct current. Accordingly on subsequent movement of the track relay contact 53 between its picked up and released positions the two end portions of the primary winding 54 of transformer 16DT are alternately energized and current is induced in the secondary winding 57.

In addition at this time the connections through which energy was supplied through track relay contact 53 to the windings of relays 16A, 16G, and 16H are interrupted so that after the contact 56 of relay 16H completes the circuit of the transformer primary winding the track relay contact 53 serves only to control the supply of energy to the transformer primary winding.

At this time as the windings of the relays 16A, 16G, and 16H are disconnected from the circuits associated with the track relay contact 53, the release time and operating characteristics of the relays are not affected by the transformer primary winding 54, as would be the case if the relay windings continued to be connected to the circuits through which energy is supplied to the transformer primary winding.

As the track relay 16TR is responding to energy of the 75 code frequency, the frequency of the current induced in the secondary winding 57 of

decoding transformer 16DT is not such as to effect picking up of the contacts of relay 16J.

It will be seen also that on picking up of contact 62 of relay 16F, which occurred on the second picked up period of the track relay contacts, the circuit for supplying steady uncoded energy to the transformer 15TT was established, and is traced from terminal BX of the source of current through back contact 61 of relay 16G, and front contact 62 of relay 16F to a terminal of the winding 64, the other terminal of which is connected to terminal CX of the source of signal control energy.

The steady energy supply circuit is interrupted on picking up of contact 61 of relay 16G, which occurs on the second released period of the track relay contacts, while on picking up of contact 61 of relay 16G the circuit for supplying energy of the 180 code frequency to the transformer 15TT is partially completed, and becomes complete when the contact 60 of relay 16H becomes picked up.

On continued movement of the train through the track stretch so that it clears section 17T, the equipment associated with the track relay for that section operates in the manner described in detail above in connection with section 16T, and energy of the 180 code frequency is supplied to the section 16T. On the resultant more rapid operation of the contacts of the relay 16TR sufficient energy is passed by the resonant unit 16RUA to effect picking up of the contact of relay 16J to thereby extinguish the yellow lamp Y of signal 16S and establish a circuit to illuminate the green lamp G of the signal.

The normal operation of the equipment shown in Fig. 2 on passage of a train having been described, its operation in the event an insulated joint breaks down as a result of passage of a train will now be considered.

Operation of equipment in the event an insulated joint breaks down as a result of passage of a train

If a train traveling in the normal direction of traffic enters the track section 16T, and an insulated joint 3 separating sections 15T and 16T breaks down as a result of the passage of the train, the track relay 16TR will be shunted, as explained in detail above, and the auxiliary relays associated therewith will be deenergized, while the signal lamp R of the signal 16S will be lighted, and energy of the 15 code frequency will be supplied to the transformer 15TT.

As long as any portion of the train remains in section 15T, the track relay of that section will be shunted, but when the rear of the train clears section 15T, the coded energy supplied to the track rails of that track section will feed to the track relay for section 15T and the equipment associated therewith will be conditioned to cause the yellow lamp of the signal therefor to be lighted, and to supply coded energy of the 180 coded frequency to the adjacent section in the rear.

In electrified territory, because of the well-known operation of the impedance bonds 4, breaking down of one insulated joint has the same effect as breaking down of both insulated joints in steam propulsion territory, and permits the impulses of signal control current supplied to the section in the rear of the defective joint to feed to the track relay of the section in advance of the defective joint.

Because of the defective joint 3, therefore,

coded energy supplied to the rails of section 15T will feed over the defective joint, but because of the shunting action on the wheels and axles of the train, insufficient energy will be supplied to the track relay 16TR to effect code following operation thereof until the train has advanced far enough in the track stretch for the rear of the train to be located a substantial distance in advance of the track relay 16TR.

When a train has advanced this far, the contacts of the track relay 16TR will be picked up by an impulse of energy feeding over the defective joint from section 15T.

On the first picked up period of the track relay contacts, energy is supplied to the winding of relay 16A over the circuit which is traced from terminal B of the source of current through front contact 53 of the track relay 16TR, back contact 69 of relay 16F, back contact 40 of relay 16G, and winding of relay 16A to terminal C of the source of current.

As a result of the supply of energy to the winding of relay 16A, contact 42 of this relay becomes picked up so that on the first released period of the track relay contacts following their first picked up period, energy is supplied over contact 44 of the track relay to charge the condenser 16EC. As a result, on the next or second picked up period of the track relay contacts, energy is supplied from the condenser 16EC to the winding of relay 16F and effects picking up of the contacts of this relay.

On picking up of contact 62 of relay 16F the steady energy or "lockout" circuit for supplying steady uncoded energy to the transformer 15TT is established, and is traced from terminal BX of the source of signal control current through back contact 62 of relay 16G, and front contact 62 of relay 16F to one terminal of the winding 64 of transformer 15TT, the other terminal of which is connected to terminal CX of the source of signal control energy.

As a result of the supply of steady uncoded energy to the transformer 15TT, steady energy is fed to the track rails of section 15T and feeds therefrom over the defective insulated joint 3 to maintain the contacts of the track relay 16TR constantly picked up.

As the contacts of relay 16TR are constantly picked up, and as the contacts of relay 16F are picked up while the contacts of relay 16G are released, a holding circuit is complete to supply energy to the winding of relay 16F to maintain the winding of that relay energized. This holding circuit is traced from terminal B of the source of current through front contact 53 of relay 16TR, front contact 69 of relay 16F, and back contact 70 of relay 16G to one terminal of the winding of relay 16F, the other terminal of which is connected to terminal C of the source of current. As the winding of relay 16F is constantly energized, the contacts of the relay are maintained picked up and contact 62 maintains the steady energy or "lockout" circuit to supply steady uncoded energy to the transformer 15TT.

From the foregoing it will be seen that if an insulated joint breaks down as a result of passage of a train, then coded energy supplied to the section in the rear of the defective joint will feed over the joint and operate the track relay of the section in advance of the defective joint. As a result of such operation of the track relay by current feeding over the defective joint, the steady energy or "lockout" circuit will be established on the second picked up period of the

contacts of the track relay of the section in advance of the defective joint, while as a result of the supply of steady energy, the contacts of the track relay for the section in advance of the defective joint will be held picked up and the relay 16F will be continuously energized and will maintain the steady energy or "lockout" circuit.

At this time the relay 16H is deenergized and its contact 65 is released to establish the circuit for illuminating the red or stop lamp R of the signal 16S.

As the train proceeds through the track stretch and enters section 17T, the track relay for that section is shunted, and the signal for the section is conditioned to display its red or stop indication, while current of the 75 code frequency is supplied to the transformer 16TT. When the rear of the train clears section 16T, the impulses of energy supplied by the transformer 16TT feed to the track relay 16TR, but at this time the intervals between impulses of energy supplied by the transformer 16TT are filled by the steady energy feeding over the defective insulated joint from section 15T with the result that the contacts of the track relay 16TR are maintained steadily picked up. Accordingly relay 16F continues to be energized, while the contacts of relay 16H remain released and condition the signal 16S to display its red or stop indication.

The same condition continues when the train advances far enough to clear section 17T, in which event the track relay for the section 17T conditions the signal associated therewith to display its yellow or caution indication, while current of the 180 code frequency is supplied to the rails of section 16T. At this time since steady energy feeds over the defective insulated joint from section 15T, the contacts of the track relay 16TR are steadily picked up and no change occurs in the aspect of the signal 16S.

It will be seen that when the "lockout" circuit is established and the contacts of relay 16F are picked up, contact 69 of relay 16F interrupts the circuit for energizing the winding of relay 16A, and the contacts of this relay thereupon become released. This is advantageous where the relay 16A is employed to control an interlocking relay for controlling a highway crossing signal. Where such control is employed, the relay 16A when energized establishes a circuit to supply energy to the winding of the interlocking relay. This circuit is interrupted when the contacts of the relay 16A are released which is the condition when the "lockout" circuit is established.

The operation of the equipment shown in Fig. 2 if an insulated joint breaks down as a result of passage of a train having been described, the operation of the equipment if an insulated joint breaks down while the track stretch is vacant will now be considered.

Operation of the equipment if an insulated joint breaks down when the track stretch is vacant

For purposes of illustration it will be assumed that the track stretch is vacant and that energy of the 180 code frequency is being supplied to the rails of section 16T. As a result, all of the auxiliary relays associated with track relay 16TR are energized, while the signal 16S will be conditioned to display its green or proceed indication, and energy of the 180 code frequency is supplied to the rails of section 15T.

When the insulated joint 3 separating sections 15T and 16T becomes defective, impulses of energy supplied to the rails of section 15T feed

over the defective joint and energize the track relay 16TR.

If at the time the joint 3 becomes defective the impulses of code supplied to the section 15T are out of step with those supplied to the section 16T, the impulses of code supplied to section 15T will fill in the "off" periods in the code supplied to section 16T with the result that the contacts of track relay 16TR will be maintained picked up all or substantially all of the time.

If at the time the insulated joint separating sections 15T and 16T becomes defective the impulses of code supplied to the two sections are substantially in step with each other they will soon become out of step. This will be true because the code transmitters which create the code for the two sections are driven by electric motors and these motors will not operate at exactly the same speed. Accordingly if the track relay contacts are not held picked up for an abnormally large proportion of the time as a result of the unusually high value of current supplied to the relay winding when the code impulses are substantially in step with each other, the track relay contacts will soon be held picked up an abnormally large portion of the time because of the increase in the time during which energy is supplied to the track relay winding when the two codes get out of step.

In consequence of the lengthened picked up periods of the track relay contacts, too little or no current is supplied to charge the condenser 16EC with the result that little or no current is available to energize the winding of relay 16F.

As a result, the contacts of relay 16F become released, and on release of contact 47 of the relay, the circuit for energizing the winding of relay 16G is interrupted, while on release of contact 62 of the relay 16F the circuit for supplying energy of the 180 code frequency to the transformer 16TT is interrupted.

On release of contact 47 of relay 16F the circuit for energizing the winding of relay 16G and for connecting the snubbing resistor 48 across the terminals of the winding of relay 16G is interrupted, and the contacts of relay 16G quickly become released.

On release of contact 51 of relay 16G the circuit for energizing the winding of relay 16H is interrupted, while on release of contact 40 of relay 16G the circuit for energizing the winding of relay 16A is interrupted.

In addition on release of contact 61 of relay 16G the circuit for supplying energy of the 75 code frequency to the rails of section 15T is complete and current of this code frequency is supplied to that section.

The energy of 75 code frequency supplied to section 15T feeds over the defective joint 3 to the track relay 16TR and combines with the energy of 180 code frequency supplied to the rails of section 16T by the transformer 16TT with the result that the contacts of the track relay 16TR will remain picked up and energy will be supplied to the winding of relay 16A to cause the contact 42 of that relay to be picked up. The circuit for supplying energy to the winding of relay 16A is traced from terminal B of the source of current through front contact 53 of the track relay 16TR, back contact 69 of relay 16F, back contact 40 of relay 16G, and winding of relay 16A to terminal C of the source of current.

As a result of the supply of energy of two different code frequencies to the rails of section 16T, that is, energy of 180 code frequency sup-

plied through the transformer 15TT, and energy of the 75 code frequency feeding over the defective joint from section 15T, a time will soon come when a relatively long "off" interval will occur in the code, and the contacts of the track relay 16TR will be released for a substantial period of time so that contact 44 will engage its back contact long enough for a substantial charge to be built up between the elements of the condenser 16EC.

The contacts of the track relay will soon thereafter become picked up again and energy will be supplied from the condenser 16EC to the winding of relay 16F to effect picking up of the contacts of relay 16F. As soon as the contacts of relay 16F are picked up, a stick circuit is established to maintain the relay winding energized, this stick circuit including front contact 53 of relay 16TR, front contact 69 of relay 16F, back contact 70 of relay 16G, and winding of relay 16F to terminal C of the source of current.

As a result of picking up of the contacts of relay 16F, contact 62 is picked up and establishes the "lockout" or steady energy supply circuit to supply steady uncoded energy to the transformer 15TT. This steady energy feeding over the defective joint 3 to the track relay 16TR will maintain the track relay contacts picked up with the result that the holding circuit for the winding of relay 16F will be maintained and relay 16F will operate to maintain the "lockout" circuit.

As contact 69 of relay 16F is picked up at this time, the previously traced circuit for energizing the winding of relay 16A is interrupted and the contact 42 of this relay becomes released, but the relay 16F is maintained energized by current supplied over the stick circuit traced above.

At this time the winding of relay 16H is deenergized and the contact 65 of this relay remains released to maintain the circuit for lighting the red or stop lamp R of the signal 16S.

Operation of the equipment in the event the lockout circuit is interrupted

The system provided by this invention is arranged so that if while the "lockout" circuit is established it is improperly interrupted for any reason, it will be automatically restored.

If the lockout circuit is temporarily interrupted for any reason, as for example shorting of the wire leading to the primary winding 64 of transformer 15TT, or disconnection of this wire caused by a loose connection, the supply of energy to the rails of section 15T will be interrupted. A similar condition results if one of the wires connecting the track relay 16TR with the rails of section 15T is temporarily disconnected or short-circuited at a time when the "lockout" is in effect.

On interruption of the supply of current to the rails of section 15T the track relay 16TR will respond to coded energy supplied by the transformer 15TT.

On the first "off" period in the code supplied by the transformer 15TT following the interruption of the "lockout" circuit, the track relay contacts become released and energy is supplied to the winding of relay 16G over the circuit which is traced from terminal B of the source of current through back contact 53 of relay 16TR, back contact 45 of relay 16G, and front contact 47 of relay 16G, to one terminal of the winding of relay 16G, the other terminal of which is connected to terminal C of the source of current.

As a result of energization of the winding of 75

relay 16G, the contacts of the relay are picked up and the circuit is established to supply current to the winding of relay 16A, while, in addition, the stick circuit for supplying energy to the winding of relay 16F is interrupted, and the stick circuit for maintaining the winding of relay 16G energized is established.

Also, on picking up of the contacts of relay 16G, contact 61 interrupts the "lockout" circuit, while contact 51 of the relay establishes a circuit to supply energy to the winding of relay 16H on the next picked up period of the track relay contacts.

On picking up of contact 40 of relay 16G energy is supplied to the winding of relay 16A and the contact of this relay becomes picked up. On picking up of contact 42 of relay 16A, the contact 44 of relay 16TR being in its released position energy is supplied to the condenser 16EC, but the length of time during which energy is supplied to the condenser before the contacts of the track relay become picked up again is relatively brief and the condenser may be only partially charged.

On the next picked up period of the track relay contacts energy is supplied from the condenser 16EC to the winding of relay 16F, but because of the low value of the charge on the condenser 16EC, insufficient energy may be supplied to the winding of relay 16F to maintain the contacts of relay 16F picked up until the next impulse of current is supplied to the relay winding and the contacts of relay 16F may become released during the next "off" interval in code.

On the first picked up period of the track relay contacts, that is, the period under consideration, energy is supplied to the winding of relay 16H over the circuit which is traced from terminal B of the source of current through front contact 53 of relay 16TR, back contact 50 of relay 16H, front contact 51 of relay 16G, and winding of relay 16H to terminal C of the source of current.

On picking up of the contacts of relay 16H contact 50 establishes the stick circuit for the relay winding, while contact 60 of the relay completes the circuit for supplying energy of the 180 code frequency to the wire leading to the track transformer 15TT. Since it is assumed that the circuit for supplying energy to the transformer 15TT is interrupted, this energy will not reach the transformer.

If the contacts of relay 16F remain picked up during the second "off" period in the code, the circuits for energizing the windings of the relays 16A, 16G, and 16H will be maintained, while the winding of relay 16F will be supplied with impulses of energy during subsequent picked up periods of the track relay contacts, and the contacts of all the auxiliary relays will be maintained picked up as long as the track relay continues to respond to energy supplied by transformer 15TT.

As pointed out above, the contacts of relay 16F may become released during the second "off" interval in the code, and if they do, contact 62 of relay 16F will interrupt the circuit for supplying energy of the 180 code frequency.

If the contacts of relay 16F become released at this time, the contacts of the relays 16A, 16G, and 16H will become released, while these relays and relay 16F will be energized serially if the track relay 16TR continues to respond to coded energy, and these relays will thereafter remain energized as long as normal code following operation of the track relay continues.

If the supply of energy to the transformer

15TT is now restored, the coded energy feeding over the defective insulated joint from section 15T to the track relay 16TR will cause the contacts of the track relay to remain picked up for an abnormally large portion of the time, as explained above, with the result that insufficient energy is supplied to the condenser 16EC to energize the relay 16F. The contacts of the relay 16F, therefore, will become released effecting release of the contacts of the auxiliary relays associated therewith, while relay 16F will subsequently become energized, and its contacts will be picked up to establish the "lockout" circuit as explained above.

Modification shown in Fig. 3 of the drawing

In Fig. 3 of the drawing there is shown a modified arrangement which I may incorporate in the system shown in Fig. 2. In the modification shown in Fig. 3 the relay 16FA, which takes the place of the relay 16F employed in the system shown in Fig. 2, is provided with two windings instead of the one winding with which the relay 16F is provided.

The relay 16FA has a winding 75 to which energy is supplied from the condenser 16EC, and a winding 76 to which energy is supplied through the stick circuit for the relay. A snubbing resistor 77 is shunted across the winding 75 of the relay 16FA to render the relay contacts slow in releasing.

The wire leading from one element of the condenser 16EC is connected to the winding 75 of the relay 16FA and also to terminal C of the source of current, while the wire leading from front contact 44 of the track relay 16TR is connected to the other terminal of the winding 75. Accordingly, when the contacts of the track relay 16TR are responding to coded energy, current impulses are supplied from the condenser 16EC to the winding 75 to maintain the contacts of the relay 16FA picked up.

The wire leading from back contact 70 of relay 16G is connected to one terminal of the winding 76 of relay 16FA, while the other terminal of this winding is connected to terminal C of the source of current. As a result, when the contacts of the track relay 16TR are picked up and the contacts of relay 16G are released, the stick circuit for maintaining the contacts of relay 16FA picked up is established and this circuit serves to energize the winding 76.

The operation of the system shown in Fig. 3 is substantially the same as that shown in Fig. 2 and a detailed description of the operation thereof is unnecessary.

Operation of the system shown in Fig. 2 of the drawing on the supply of steady energy to a track circuit

In the system shown in Fig. 2 of the drawing steady energy may be supplied to the rails of section 16T as a result of establishment of the "lockout" circuit controlled by the track relay of the adjacent section in advance. Steady energy may also be supplied to the rails of a section similar to section 16T to discontinue operation of a highway crossing signal, not shown, as explained in detail in the application of Ralph R. Kemmerer identified above, or steady energy may be supplied to a track relay as a result of operation of back contact coding facilities.

For purposes of illustration it will be assumed that an insulated joint 3 separating sections 16T and 17T breaks down as a result of passage of

5 a train moving in the normal direction of traffic, and that the equipment associated with section 17T operates to establish the "lockout" circuit to supply steady uncoded energy to the rails of section 16T.

10 As explained above in connection with the equipment associated with section 16T, when a train enters a section, the equipment associated with that section is conditioned to supply energy of the 75 code frequency to the track rails of the adjacent section in the rear, but the impulses of energy of this code frequency do not feed to the track relay of such section in the rear until the rear of the train has cleared that

15 section.

Accordingly, when the train moving in the normal direction of traffic enters section 17T, impulses of energy of the 75 code frequency are supplied to the track transformer 16TT, but do not reach the track relay 16TR until the rear of the train vacates section 16T. Thereafter there is a short time interval before the train will have advanced far enough in the section 17T for the contacts of the track relay for that section to be picked up by impulses of current feeding over the defective joint from section 16T. In this interval code following operation of the track relay 16TR will occur and the relays 16A, 16F, 16G, and 16H will be serially energized in the manner explained in detail above.

20 When the train has advanced far enough in section 17T for the track relay of that section to be energized by current feeding over the defective insulated joint, the equipment associated with the track relay for section 17T will operate to establish the "lockout" or steady energy supply circuit, and steady energy will be supplied to the rails of track section 16T, and thereafter the contacts of relay 16TR will be maintained constantly picked up.

25 As a result of the supply of steady energy to the track relay 16TR at a time when the relays 16A, 16F, 16G, and 16H are all energized, the contact 44 of relay 16TR will not periodically engage its back contact to effect the supply of energy to the condenser 16EC, and hence the charge on this condenser will not be periodically restored and energy will not be available to energize the winding of relay 16F.

30 As a result, the contacts of relay 16F will become released, and on opening of contact 47 thereof the circuit for energizing the winding of relay 16G will be interrupted to thereby cause the contacts of that relay to become released.

35 As a result of the release of the contacts of relay 16G, the circuit for energizing relay 16H is interrupted, while contact 40 completes the circuit to energize relay 16A, which circuit is complete at this time since contact 69 of relay 16F is released and contact 53 of the track relay 16TR is picked up.

40 As a result of the release of contact 62 of relay 16F and contact 61 of relay 16G, the circuit for supplying energy of the 75 code frequency to the track transformer 15TT is complete, and energy of this frequency is therefore supplied to the rails of section 15T.

45 At this time as the contacts of relay 16A are picked up, a contact of this relay may be employed to establish a circuit to energize the winding of an interlocking relay, not shown, which may control a highway crossing signal, not shown.

50 In addition, as the contact 42 of relay 16A is

picked up, the equipment is in condition to quickly respond to code following operation of the track relay 16TR, such as might occur when the train clears the section in advance of section 16T and the supply of steady energy to the rails of section 16T is discontinued where the steady energy was supplied to discontinue operation of a highway crossing signal.

Under such circumstances, on the first released period of the track relay contacts following the period in which they were constantly picked up, energy is supplied to charge the condenser 16EC, and on the first picked up period of the track relay contacts, energy is supplied to the winding of relay 16F, and thereafter the relays 16G and 16H are energized serially, as explained in detail above.

From the foregoing, it will be seen that the signaling system shown in Fig. 2 of the drawing is arranged to provide the "lockout" or steady energy circuit to supply steady uncoded energy to the section in the rear of a defective insulated joint, while the system also operates so that if steady energy is supplied to a section by means other than the "lockout" circuit controlled by the track relay of that section, the equipment for that section will not operate to repeat the supply of steady energy to the section in the rear thereof, but will supply coded energy to that section.

This prevents any cascading action and makes it unnecessary to employ special cut section facilities to accomplish this purpose. It also makes it possible to employ steady uncoded energy for the purpose of discontinuing operation of highway crossing signals where such is desired.

From the foregoing it will be seen that this invention provides improved code detecting means including a relay which is energized only after a plurality of movements of the code following track relay contacts between their two positions.

It will be seen also that this invention provides a signaling system incorporating this improved code detecting means and arranged to prevent a flash of the yellow or caution lamp when a train enters a section to which steady uncoded energy is supplied, and furthermore that the invention provides an improved non-cascading "lockout" circuit employing the improved code detecting means.

Although I have herein shown and described only three forms of apparatus embodying my invention, it is understood that various changes and modifications may be made therein within the scope of the appended claims without departing from the spirit and scope of my invention.

Having thus described my invention, what I claim is:

1. In a coded railway signaling system, in combination, a stretch of railway track having a pair of track rails divided by insulated joints into successive track sections including a forward and a rearward section, means governed by traffic conditions in advance of the forward section for at times supplying periodically interrupted energy and at other times supplying steady energy to the rails of said forward section, a code following track relay having a winding receiving energy from the rails of said forward section, a first, a second and a third auxiliary relay and an energy storage device associated with said track relay, a circuit including a front contact of the track relay for supplying energy to the winding of the first auxiliary relay, a circuit including a front contact of the first auxiliary relay and a back contact of the track relay for supplying current to the energy storage device, a circuit including a front contact of the track relay for supplying current from the energy storage device to a winding of the second auxiliary relay, a circuit including front contacts of the track relay and of the second auxiliary relay and a back contact of the third auxiliary relay for also supplying energy to a winding of the second auxiliary relay, a circuit including a back contact of the track relay and a front contact of the second auxiliary relay for supplying energy to the winding of the third auxiliary relay, a circuit operative when the contacts of both the second and the third auxiliary relays are released to supply periodically interrupted energy to the rails of said rearward section, a circuit including a front contact of the second auxiliary relay and a back contact of the third auxiliary relay for supplying steady energy to the rails of said rearward section, and a circuit established on continued code following operation of said track relay subsequent to establishment of said steady energy supply circuit to supply periodically interrupted energy to the rails of said rearward section.

2. In a coded railway signaling system, in combination, a stretch of railway track having a pair of track rails divided by insulated joints into successive track sections including a forward and a rearward section, means governed by traffic conditions in advance of the forward section for at times supplying periodically interrupted energy and at other times supplying steady energy to the rails of said forward section, a code following track relay having a winding receiving energy from the rails of said forward section, a first, a second and a third auxiliary relay and an energy storage device associated with said track relay, a circuit including a front contact of the track relay for supplying energy to the winding of the first auxiliary relay, a circuit including a front contact of the first auxiliary relay and a back contact of the track relay for supplying current to the energy storage device, a circuit including a front contact of the track relay for supplying current from the energy storage device to a winding of the second auxiliary relay, a circuit including front contacts of the track relay and of the second auxiliary relay and a back contact of the third auxiliary relay for also supplying energy to a winding of the second auxiliary relay, a circuit including a back contact of the track relay and a front contact of the second auxiliary relay for supplying energy to the winding of the third auxiliary relay, a circuit operative when the contacts of both the second and the third auxiliary relays are released to supply periodically interrupted energy to the rails of said rearward section, a circuit including a front contact of the second auxiliary relay and a back contact of the third auxiliary relay for supplying steady energy to the rails of said rearward section, and a circuit established on continued code following operation of said track relay subsequent to establishment of said steady energy supply circuit to supply periodically interrupted energy to the rails of said rearward section.

3. In a coded railway signaling system, in combination, a stretch of railway track having a pair of track rails divided by insulated joints into successive track sections including a forward and a rearward section, means governed by traffic conditions in advance of the forward section for at times supplying periodically interrupted energy and at other times supplying steady energy to the rails of said forward section, a code following track relay having a winding receiving energy from the rails of said forward section, a first, a second and a third auxiliary relay and an energy storage device associated with said track relay, a circuit including a front contact of the track relay for supplying energy to the winding of the first auxiliary relay, a circuit including a front contact of the first auxiliary relay and a back contact of the track relay for supplying current to the energy storage device, a circuit including a front contact of the track relay for supplying current from the energy storage device to a winding of the second auxiliary relay, a circuit including front contacts of the track relay and of the second auxiliary relay and a back contact of the third auxiliary relay for also supplying energy to a winding of the second auxiliary relay, a circuit including a back contact of the track relay and a front contact of the second auxiliary relay for supplying energy to the winding of the third auxiliary relay, circuits operative when the contacts of both the second and the third auxiliary relays are picked up or when the contacts of both relays are released to supply periodically interrupted energy to the rails of said rearward section, and a circuit including a front contact of the second auxiliary relay and a back contact of the third auxiliary relay for supplying steady energy to the rails of said rearward section.

4. In a coded railway signaling system, in combination, a stretch of railway track having a pair of track rails divided by insulated joints into successive track sections including a forward and a rearward section, means governed by traffic conditions in advance of the forward section for at times supplying periodically interrupted energy and at other times supplying steady energy to the rails of said forward section, a code following

track relay having a winding receiving energy from the rails of said forward section, a first, a second, a third, and a fourth auxiliary relay and an energy storage device associated with said track relay, a circuit including a front contact of the track relay for supplying energy to the winding of the first auxiliary relay, a circuit including a front contact of the first auxiliary relay and a back contact of the track relay for supplying current to the energy storage device, a circuit including a front contact of the track relay for supplying current from the energy storage device to a winding of the second auxiliary relay, a circuit including front contacts of the track relay and of the second auxiliary relay and a back contact of the third auxiliary relay for also supplying energy to a winding of the second auxiliary relay, a circuit including a back contact of the track relay and a front contact of the second auxiliary relay for supplying energy to the winding of the third auxiliary relay, a circuit operative when the contacts of both the second and

the third auxiliary relays are released to supply periodically interrupted energy to the rails of said rearward section, a circuit including a front contact of the second auxiliary relay and a back contact of the third auxiliary relay for supplying steady energy to the rails of said rearward section, a circuit including front contacts of the track relay and of the third auxiliary relay for supplying energy to the winding of the fourth auxiliary relay, a circuit including a front contact of said fourth auxiliary relay for supplying periodically interrupted energy to the rails of said rearward section, a signal controlling traffic in said forward section, a circuit including a back contact of said fourth auxiliary relay for conditioning said signal to display its most restrictive indication, and a circuit including a front contact of said fourth auxiliary relay for conditioning said signal to display a less restrictive indication.

LESLIE R. ALLISON.
